UNITED STATES PATENT OFFICE

2,601,952

THREE COIN TOY REGISTER BANK

Jacob Farber, New York, N. Y.

Application June 2, 1950, Serial No. 165,813

1 Claim. (Cl. 235—100)

1

This invention relates to a coin bank.

It is an object of the present invention to provide a coin bank wherein nickels, dimes and quarters can be inserted into the same opening in the bank shell and will register automatically the exact amount which has been inserted, and wherein, when the bank has been filled with coins amounting to ten dollars, the pull down cover can be opened to dispense the contents of the bank.

Other objects of the present invention are to provide a coin bank of this type which is of simple construction, inexpensive to manufacture, has a minimum of parts, compact, easy to operate, and efficient in operation.

For other objects and for a better understanding of the invention, reference may be had to the following detailed description taken in connection with the accompanying drawing, in which:

Fig. 1 is a perspective view of a coin bank embodying the features of the present invention.

Fig. 2 is a vertical sectional view taken on line 2—2 of Fig. 1.

Fig. 3 is a vertical sectional view taken on line 3—3 of Fig. 2.

Fig. 4 is a fragmentary horizontal sectional view taken on line 4—4 of Fig. 2.

Fig. 5 is a perspective view of the coin receiving and sliding member and of the registering discs.

Fig. 6 is a fragmentary horizontal sectional view of the coin support with a nickel in place and with portions broken away to show certain of the parts.

Fig. 7 is a fragmentary view similar to Fig. 6 with the slide pulled over to carry the coin in such a manner as to move the fingers into engagement with the star wheel.

Fig. 8 is a perspective view of the member having the fingers for engaging the star wheel.

Fig. 9 is a fragmentary plan view showing the extent to which the finger member is moved when a dime is inserted and with the finger which is used for engaging the star wheel when the dime is used being extended over the star wheel.

Fig. 10 is a fragmentary top plan view showing the finger moved in for engagement of the finger used for the quarter, in this instance there being a double projection of fingers to effect movement of the star wheel in five steps.

Referring now to the figures, 15 represents a front casing member from which extends rearwardly a bottom member 16. Surrounding the open ends and closing off the rear part of the

2

front casing member 15 is a rear casing 17. The front casing has a top horizontal portion 18 with a segmental shaped opening 19 therein and with an elongated slot 21 through which an operating handle 22 may slide. In the lower part of the front casing 15 is a door 23 which has a handle 24 and which can be pulled down only after a predetermined account of ten dollars has been placed in the bank. This door opening has an inwardly bent flange 25 with openings 26 therein for receiving upstanding projections 27. The door also has a projection 28 to which a tension spring 29 is connected. The opposite end of the tension spring is connected to a struck-up lug 31 on the bottom portion 16, Fig. 2.

The ends of the door 23 are provided with inwardly extending hook formations 32 and 33 of different sizes which may register respectively with slots 34 and 35 of the respective number registering discs 36 and 37.

These discs 36 and 37 are carried upon an inner frame 39 that is of inverted L shape and which is connected by a tab 41 to the bottom portion 16 and by tabs 42 which pass through the top portion 18 whereby to hold the frame 39 in place.

The large disc 36 is pivotally connected upon the frame member 39 by bolt means 43. A ratchet or star wheel 44 is connected to the disc 36 having teeth projections 45 adapted to be engaged by finger projections 47, 48 or 49 of a finger member 50. The finger member 50 is secured to a slide 51 to which the handle or operating member 22 is connected. Frame 39 has a horizontal portion 52 which carries the slide 51 and this portion 52 has an opening 53 through which the finger member 50 downwardly projects. The finger member 50 is connected to the slide 51 so that it can be bent or angled toward the star wheel 44 when a coin resting on the horizontal portion 52 is drawn into engagement with a guide 54 carried by the horizontal portion 52 and made secure therewith by bolt means 55. A tension spring 56 is connected between the slide 51 at 57 thereon and a hook projection 58 of the horizontal portion 52. The slide 51 has a depending flange 59 for engaging the coin in order to force the same over the guide 54.

As shown in Fig. 6, a nickel is placed in the opening 19 and rests upon the horizontal portion 51. This nickel will engage the guide 54 so that the finger member 50 is bent inwardly to cause the engagement of the finger projection 47 with the star wheel 44 so as to step the star wheel a single notch and to give a five cent

registration in openings 61 and 62 in the front casing 15. If a dime is placed therein, as shown in Fig. 9, projection 48 will engage the star wheel in a position so as to adjust the star wheel two steps as the slide 51 is moved. If twenty five cents is inserted, the finger arm 50 will be projected in such a manner as to cause both fingers 47 and 49 to engage the teeth projection 45 in succession so that the disc 36 is moved through five steps. A spring 63 engages with the teeth projections 45 so as to hold the disc against rearward rotation. The disc 36 has a projection 64 that engages, upon each revolution of the disc 36, a projection 65 which will rotate disc 37 one tenth of a turn to give a dollar indication in opening 66 of the front casing 10. A spring 67 carried by the frame 39 engages with the projections 65 to hold the disc 37 against return rotative movement. When the disc 36 has made ten revolutions, the disc 37 will have made one revolution and the slots 34 and 35 of the respective discs will be so aligned that the projections 32 and 33 of the door 23 can pass through the discs to allow the door 23 to be dropped and the contents of the bank poured outwardly thereof. The horizontal portion 51 of the frame has an opening 68 through which the coin can be passed and deposited on the bottom of the casing member 15. The disc 37 is pivotally connected to the frame 39 by pivot bolt means 70.

It should now be apparent that there has been provided a coin bank which will receive different denominations of coins through the same openings and when the operating member is moved, the exact amount will be registered.

While various changes may be made in the detail construction, it shall be understood that such changes shall be within the spirit and scope of the present invention as defined by the appended claim.

I claim:

A coin register bank adapted to receive coins of a plurality of diameters comprising a casing including horizontal top and bottom walls, a rear wall, a front wall having at least the upper por-

tion thereof vertical, and end walls, an inverted L-shaped frame secured in said casing with the vertical portion thereof positioned in a vertical plane adjacent said upper portion of said front wall and with the horizontal portion of the frame positioned adjacent but spaced from said top wall, a vertical rotatable indicating disc pivoted to the vertical frame portion parallel therewith, said upper portion of said front wall having an opening through which readings on said disc can be taken, a horizontal slide slidably mounted in said horizontal frame portion, said top wall having an opening through which a coin may be deposited on said slide, a yieldable substantially horizontal finger extending from the slide and normally substantially parallel with said guide, said finger having a corresponding plurality of projections extending substantially at right angles from said finger in a direction toward said disc, said projections having lengths differing from each other, the coin upon being moved by the slide engaging with said guide and with said finger to bend the latter outward a predetermined distance proportional to the diameter of the coin, said disc having a star wheel rigid thereon and parallel therewith and provided with gear teeth engageable by certain of said projections depending upon the extent to which said finger has been outwardly extended by the coin, and spring means between said frame and said slide for restoring said slide to its original position upon release thereof.

JACOB FARBER.
